INVENTOR

ATTORNEYS.

UNITED STATES PATENT OFFICE.

GEORGE W. LUTZ, OF WHEELING, WEST VIRGINIA, ASSIGNOR OF ONE-HALF
TO JOHN S. TRIMBLE, OF SAME PLACE.

STEAM-GENERATOR.

SPECIFICATION forming part of Letters Patent No. 282,584, dated November 13, 1883.

Application filed July 23, 1883. (No model.)

To all whom it may concern:

Be it known that I, GEORGE W. LUTZ, a resident of Wheeling, in the county of Ohio and State of West Virginia, have invented certain new and useful Improvements in Steam-Generators; and I do hereby declare that the following is a full, clear, and exact description of the invention, which will enable others skilled in the art to which it appertains to make and use the same, reference being had to the accompanying drawings, and to letters of reference marked thereon, which form a part of this specification.

This invention relates to that class of steam-generators that are used for house-heating purposes; and it consists of the combination and arrangement of the various parts, as herein-after more fully set forth and claimed.

In the drawings, Figure 1 is a vertical central section of my invention on line A A, and Fig. 2 is a cross-section on line X X. Figs. 3 and 4 are enlarged details of construction.

Like letters of reference refer to like parts. The steam-generator is composed of three principal parts—viz., the furnace or combustion chamber F, the boiler K, and steam-dome E—the whole being cylindrical in form and resting on a base, J, and surrounded by a brick wall, B. C represents the outer case or jacket of the boiler proper, provided with a head, P. Inside of this case is the furnace F, made somewhat smaller in diameter than the boiler, to admit of an annular water-space between the two walls. The bottom edge of the furnace is enlarged to same diameter as the case of the boiler and riveted together to make a watertight joint.

R is the crown-sheet of the furnace, riveted to the top edge of the case D.

In the center of the head of the boiler is a pipe, N, which connects the boiler with the steam-dome E, which is placed directly over the boiler, but a short distance above. This pipe is screw-threaded on the ends, and screws into the head of the boiler and bottom of the steam-dome.

T is the wall of the steam-dome. n is the top, and m is the bottom, both riveted to the outer case.

On the outside of the boiler, and connecting with the same at the bottom of the case, are a

series of water-tubes marked e e. These pipes extend upward and connect with the bottom of the steam-dome. Their ends are screw-threaded, so they can be readily removed when required to take the apparatus apart. The lower end is connected by means of a screw-threaded elbow-nipple, d, jam-nut e, and packing-ring f. When it is required to remove the dome, the tubes are screwed downward into the nipple until the top end is unscrewed from the bottom of the dome, after which the dome is turned around until it unwinds itself from the central connection, and can then be removed.

M is a stay-rod passing through the center of the steam-dome and boiler. This stay-rod is in two lengths. The lower portion has one end riveted to the crown-sheet of the furnace, and the other end enlarged and fitted with a screw-threaded bore to receive the threaded end of the upper portion, (shown fully in Fig. 4,) one end of which passes through the head of the steam-dome and is provided with a threaded nut. This construction of the stay-rod allows the dome to be removed by simply unscrewing the upper portion of the stay-rod, and avoids the liability of causing a leak, where the lower end of the rod is riveted to the top of the furnace, by careless handling, as would be the case if the rod were in one length.

g g are small stay-rods to stiffen the bottom and top of the steam-dome.

b b are a series of short-length fire-tubes extending from the top of the furnace through the boiler. The fire and smoke pass upward through these tubes into the space under the steam-dome, and are then deflected outward and downward around the outside of the water-tubes connecting the boiler and the steam-dome, and from the space between the furnace and brick wall the smoke passes out the smoke-flue k to the chimney.

L is a steam-pipe to convey steam to the radiators. v is the feed-water pipe to supply the boiler.

H is the grate of the furnace, of ordinary construction; G, opening for fuel.

The arrangement of the water-pipes on the outside of the boiler and the central connecting-pipe between the dome and boiler gives a perfect circulation of the water and provides

a large radiating-surface, and also admits of the apparatus being taken apart for convenience in transportation and for repairs. The boiler being less in diameter than the steam-dome gives a large hot-air space around the same without having to increase the area of the brick-work to provide for it.

The furnace being entirely surrounded by water, there is no waste heat, it being all applied to making steam, and the grate being smaller than those usually made in furnaces of this class, the consumption of fuel is proportionately less and the fire-surface greater.

The fire-tubes being of short length—about sixteen inches long—they will not choke with soot, because they are situated directly above the furnace, and the intense heat will burn the soot and prevent it from accumulating on the sides of the flues.

It will be understood that it is the intention to provide the apparatus with steam-gages, safety-valves, and such other needful appliances as are usual and well known in a steam-generator of this class, and therefore a detail description of them is not deemed necessary.

A double row of water-tubes can be placed around the boiler, in cases where it is desirable to increase the size of the generator, by simply enlarging the steam-dome.

Having described my invention, what I claim, and desire to secure by Letters Patent of the United States, is—

1. The combination of the furnace F, boiler K, the steam-dome E, situated above the boiler, with an intervening space, and connected to the boiler by means of a series of vertical water-pipes, e, around the outside of the boiler, a central pipe, N, and a stay-rod, M, arranged by screw-thread connections so that the dome can be readily removed, substantially as herein shown. 35 40

2. In a steam-generator, the combination of the furnace F, boiler K, fire-flues b b, water-tubes e, dome E, central connecting-pipe, N, central stay-rod, M, and inclosing-wall B, substantially as herein shown. 45

3. In a steam-generator, the combination of a boiler having a fire-box on the inside thereof, whereby an annular water-space is formed between the sides of the fire-box and the inner walls of the boiler, and a steam-dome mounted above the boiler and connected therewith by means of the tubes e and N, substantially as described, and for the purpose set forth. 50

In testimony that I do claim the foregoing 55 as my own I hereby affix my signature in presence of two witnesses.

GEORGE W. LUTZ.
